UNITED STATES PATENT OFFICE.

ANDREW POSPESEL, OF OSWEGO, NEW YORK

RELIEF-VALVE.

1,192,113.

Specification of Letters Patent. Patented July 25, 1916.

Application filed March 14, 1916. Serial No. 84,134.

To all whom it may concern:

Be it known that I, ANDREW POSPESEL, a citizen of the United States, residing at Oswego, in the county of Oswego and State of New York, have invented certain new and useful Improvements in Relief-Valves, of which the following is a specification.

This invention has for its object the provision of simple and efficient means whereby 10 the water of condensation in a steam heating system may be readily drained therefrom.

The invention is illustrated in the accompanying drawings and will be hereinafter 15 first fully described and then more specifically pointed out in the claim following the description.

In the drawings: Figure 1 is a plan view 20 of a device embodying my invention; Fig. 2 is a sectional elevation of the same; and, Fig. 3 is a detail end view.

In carrying out my invention, I secure to the steam heating pipe or conduit, by which the heating fluid is carried, an outlet or vent 25 pipe 1 which will preferably be threaded into a suitable opening in the said steam pipe, although it may be connected therewith in any convenient or preferred manner which will afford communication between 30 the interior of the steam pipe and the vent. To the outer end of the steam pipe, I secure a head 2 which may surround the said free end of the pipe, as shown in the drawings or be coupled thereto in any other convenient or preferred manner. This head is 35 provided at one side with a lateral guide which may conveniently be in the form of a bifurcated lug, shown at 3, and through the said guide passes the outer end of a brace 4 which has its inner end secured to a clamping collar or ring 5 passing around the pipe 1, preferably between the steam pipe and an annular shoulder on the vent pipe. The head 2 is provided with an outlet passage 6, 45 which passage communicates with the central recess or chamber 7 in the inner end of the head so as to receive the water condensing in the pipe and the outlet may be threaded to receive the end of a pipe for carrying off the water. A valve 8 is 50 provided to seat against the inner end of the passage 6 and is constructed with a stem 9 which passes through and projects beyond the end of the head, as clearly shown, a 55 spring 10 being coiled around the said stem

between the outer end of the head and a stop 11 on the stem. A packing box, indicated at 10' may be provided around the valve stem to prevent leakage, as will be readily understood. A lever 12 is pivoted at 60 its upper end to the outer end of the brace or supporting arm 4 and the lower end of this lever bears against the outer end of the valve stem, the intermediate portion of the lever being provided with an opening 65 through which a pin 13, projecting from the guide 3, extends, the lever being mounted to rock on said pin longitudinally of the same. A thumb nut 14 is mounted upon the outer end of this pin and bears against 70 the outer side of the lever so as to adjust the same, whereby the lever will always be in contact with the outer end of the stem 9 and the proper tension of the spring 10 will be maintained. The distance from the 75 point where the pin 13 passes through the lever to the pivot 15 by which the lever is attached to the brace or arm 4 should be less than the distance from the pin 13 to the end of the valve stem 9, the ratio being 80 such as will give the proper throw to the valve.

The construction and arrangement of the several parts of the device being thus made known, it is thought that the operation of 85 the same will be readily understood. The vent pipe 1 should be constructed of some material which is readily responsive to temperature changes so that it will expand and contract as the temperature of the steam 90 rises and falls. Assuming that the steam has been cut off or has fallen to a low temperature so that it condenses rapidly, the pipe 1 will contract and the contracting movement will, of course, bring the head 2 closer to the 95 inner end of the brace or supporting arm 4. The lever 12 being held on the pin 13 by the nut 14 will, of course, follow the movement of the head 2, but, as the supporting arm or brace 4 is not thermostatic like the vent pipe, 100 the lower end of the lever will swing farther than the upper portion of the same, the result being that the tension of the spring 10 will be overcome and the valve stem 9 pushed inwardly a greater distance than the 105 head 2 moves so that the valve 8 will be unseated and the water permitted to drain through the passage 6. When the steam is again turned on, the pipe 1, of course, will 110 expand and the lower or free end of the lever

12 will move outwardly, the movement being greater than the expansion of the pipe so that the valve 8 will be permitted to seat, thereby cutting off the flow through the passage 6 and, consequently, preventing the escape of steam.

It will be readily noted that I have provided an exceedingly simple device whereby the water which condenses and collects in the thermostatic pipe 1 and the chamber 7 will be permitted automatically to escape while escape and loss of steam will be automatically prevented. It will be understood, of course, that the device will be secured to the steam pipe in such a position that the natural flow of the water will be downward to the chamber 7 and thence through the passage 6 and it will also be understood that this passage 6 may be opened through the side or through the end of the head 2 or through both the side and the end. The supporting arm or brace 4 passes freely through the guide 3 and is not secured to said guide so that relative movement of the parts is permitted but the arm will be held in the plane of the axis of the thermostatic pipe and, consequently, twisting of the lever will be prevented. The device, obviously, may be applied to a heating system now already installed in a building or may be used as a part of new installations.

While the device is intended more particularly for heating systems, it may be used in apparatus for other purposes without in-

volving any departure from its essential features.

Having thus described the invention, what is claimed as new is:—

In a device for the purpose set forth, the combination of a thermostatic tube, a head fitted to and extending over the outer end of the bore of said tube and provided with a laterally projecting guide, the head being constructed with an outlet leading from the tube, a pin projecting longitudinally from the outer end of said head, a bar disposed at one side of and fixed at one end to the tube and projecting at its opposite end beyond said head and through the guide thereon, a valve seating against the inner end of the outlet from the head and having a stem passing longitudinally through the head, a lever pivoted to the outer free end of the fixed bar and having its intermediate portion mounted to oscillate on the pin, the free end of said lever bearing against the outer end of the valve stem, an adjusting nut mounted upon the said pin and bearing against the outer side of the lever, a stop on the valve stem, and a spring coiled around the valve stem between said stop and the end of the head whereby the valve will be normally seated and upon contraction of the tube will be moved longitudinally in the same and unseated.

65
In testimony whereof I affix my signature.

ANDREW POSPESEL. [L. S.]
